CLOCK

Robert C. Shipley, Kalamazoo, Mich., assignor to R. C. Shipley Mfg. Co., Portage, Mich., a corporation of Michigan

Filed Jan. 2, 1964, Ser. No. 77,999

Term of patent 14 years

(Cl. D42—7)

FIGURE 1 is a front perspective view of a clock showing my new design wherein the dial face is bordered by a plurality of horizontally-oriented parallel lines;

FIGURE 2 is a rear perspective view thereof;

FIGURE 3 is a right side elevational view thereof;

FIGURE 4 is a left side elevational view thereof;

FIGURE 5 is a top view thereof taken at right angles to the clock face;

FIGURE 6 is a rear view of FIGURE 5; and

FIGURE 7 is a front perspective view of the clock of FIGURE 1 showing a modified embodiment thereof wherein the horizontal border lines are omitted and the central dial area has intersecting, linear projections which divide the dial area into nine similarly framed, miniature squares, all as shown.

The dominant features of the design reside in the portions shown in full lines.

I claim:

The ornamental design for a clock, as shown and described.
